FIG. 1

FIG. 3

FIG. 2

FIG. 5

FIG. 4

FIG. 1 is a perspective view of a table or other similar article showing my new design;

FIG. 2 is a front elevational view thereof;

FIG. 3 is a right-side elevational view thereof;

FIG. 4 is a top plan view thereof; and

FIG. 5 is a plan view thereof, with a portion removed for convenience of illustration.

The table is characterized by the interfitting relationship between the corners of the top and the notched recesses on the upper leg portions in combination with the specific brace arrangement, all as shown.

I claim:

The ornamental design for a table or other similar article, substantially as shown and described.
